UNITED STATES PATENT OFFICE.

ELIJAH MCCOY, OF DETROIT, MICHIGAN, ASSIGNOR TO ARMSTER HAVARD, ALBERT L. STRICKER, AND MARGARET E. WARREN, ALL OF DETROIT, MICHIGAN, AND ALMA ZIENERT AND WILLIAM ZIENERT, BOTH OF JACKSON, MICHIGAN.

LUBRICATOR.

Application filed March 12, 1924. Serial No. 698,607.

To all whom it may concern:

Be it known that I, ELIJAH McCoy, a citizen of the United States, and residing at Detroit, in the county of Wayne and State 5 of Michigan, have invented a new and Improved Lubricator, of which the following is a specification.

This invention relates to lubricators especially adapted to feed graphite or similar lubricants to the steam chests of steam engines, particularly locomotive engines, and its object is to provide a lubricator of this character which may be used either alone or in combination with another or main lubricator; which will not interfere with or choke the feed of the main lubricator; which will feed no graphite while the engine is at rest; which will not get out of order; and which can be adjusted with a minimum of trouble.

20 The drawing is a central vertical section of this improved lubricator.

This lubricator is an improvement on that shown in my Patent No. 1,192,083, granted July 25, 1916, and the improvement resides 25 in the main valve and in the means for controlling it. This lubricator is again provided with a pipe A extending to the main lubricator in the cab of the locomotive which is usually connected by an independent pipe 30 to the steam dome so that it receives full boiler pressure steam whether the throttle is open or not, which is desirable as it ensures lubrication of the engines when the locomotive is coasting. A valve is provided 35 in the pipe leading to this main lubricator to avoid loss of lubricant when the locomotive is idle. The pipe A therefore conveys lubricant to the lubricator shown in the drawing and is also filled with steam under 40 substantially full boiler pressure. D is a threaded connection whereby the lubricator may be attached to the steam chest of the engine to be lubricated. The lubricator body K or container for the lubricant has a 45 threaded upper end B which is adapted to be connected to the pipe A by means of a coupling nut S. The container may be filled upon the removal of the plug L or in any other desired manner.

50 Within the lubricator is a central tube F near the lower end of which is a valve seat I on which normally rests a double-piston or dumb-bell piston valve having two end members C and H connected by a reduced

portion E. This valve is freely slideable 55 within the tube F but when on its seat it closes the port J which connects by means of a vertical passage R with the container K. A valve M having a hand wheel O controls 60 the effective capacity of the port J and is preferably provided with a needle point N to prevent the port being clogged.

The main valve is formed with a longitudinal central passage T which connects with the space between the parts C and H by 65 means of a small hole P so that the pressure between these parts is always practically the same as the pressure below the part H. A small ring V may be screwed into the upper 70 end of the tube F to limit the upward movements of the main valve and a calibrated nipple G may be screwed into the upper end of the valve.

The operation of this valve is as follows. While the engine is at rest, and probably 75 while running very slowly, the valve H remains on its seat I and prevents any lubricant passing from the chamber K. It does not prevent lubricant from passing down from the pipe A. The normal pressure of 80 the steam is on top of the upper member C of the valve and assists in holding down the main valve. When there is suction in 85 the steam chest, as when a locomotive engine is coasting without steam, the valve remains on its seat and prevents loss of lubricant.

I have noticed that when a pressure gauge is attached to the steam chest, that it shows a variation or pulsation of pressure, the maximum often being as much as five pounds 90 above that of the boiler. This is probably due to the surge of the steam which flows through the steam pipe and through the steam chest into the cylinder when the port is open, but when the port is suddenly closed 95 and before the other port is opened, this surge is sufficient to pile up a momentary excess of pressure in the steam chest, and a pressure in the lower end of the valve H which is greater than the pressure above the 100 valve plus the weight of this valve, and this excess lifts this valve from its seat, but only momentarily. This uncovers the port J and permits steam to enter the chamber K to condense and mix with the lubricant 105 and to force it downward and outward through the port J. But as soon as this back-pressure pulsation ends, the valve is

again seated by its own weight and the pressure above the valve.

Thus there will be rapid and numerous minute discharges of lubricant to the connection D, the quantities being controlled by the valve M. The ring V is adjustable and so controls the lift of the main valve. The nipple G is preferably square in cross section, as is also the reduced part W of the main valve, so that it may be gripped without marring its wearing surface when the nipple is being removed. This lubricator therefore adds a slight amount of graphite to the lubricant passing to the cylinder from the main lubricator in the cab, and supplies that very important and desirable material to the engine in a manner impossible with a hydrostatic lubricator whose limited feed passage becomes clogged with the graphite.

20 I claim:

1. In a lubricator for steam engines, the combination with a lubricant cup having a central tubular portion adapted to be connected to a steam boiler by means of a main lubricator and a pipe for conducting steam and lubricant from said main lubricator, and a chamber for graphite surrounding said central portion, said lubricator being formed with an internal valve seat adjacent the lower end of the central tubular portion and with a passage connecting said chamber and the interior of the tubular portion just above the valve seat, a manually adjustable valve to control the effective area of said passage, and a dumb-bell piston valve mounted within said tubular portion and adapted to engage said valve seat, said valve being subject to said boiler pressure at its upper end, said valve having a central longitudinal passage to permit the passage of the lubricant received from said pipe.

2. In a lubricator for steam engines, the combination with a lubricant cup having a central tubular portion adapted to be connected to a steam boiler by means of a main lubricator and a pipe for conducting steam and lubricant from said main lubricator, and a chamber for graphite surrounding said central portion, said lubricator being formed with an internal valve seat adjacent the lower end of the central tubular portion and with a passage connecting said chamber and the interior of the tubular portion just above the valve seat, a manually adjustable valve to control the effective area of said passage, a dumb-bell piston valve

mounted within said tubular portion and adapted to engage said valve seat, said valve being subject to said boiler pressure at its upper end, said valve having a central longitudinal passage to permit the passage of the lubricant received from said pipe, and a hole connecting the space around the reduced portion of the valve to its central passage.

3. In a lubricator for steam engines, the combination with a lubricant cup having a central tubular portion adapted to be connected to a steam boiler by means of a main lubricator and a pipe for conducting steam and lubricant from said main lubricator, and a chamber for graphite surrounding said central portion, said lubricator being formed with an internal valve seat adjacent the lower end of the central tubular portion and with a passage connecting said chamber and the interior of the tubular portion just above the valve seat, a manually adjustable valve to control the effective area of said passage, a dumb-bell piston valve mounted within said tubular portion and adapted to engage said valve seat, said valve being subject to said boiler pressure at its upper end, said valve having a central longitudinal passage to permit the passage of the lubricant received from said pipe, and means to restrict the movement of said piston valve.

4. In a lubricator for steam engines, the combination with a lubricant cup having a central tubular portion adapted to be connected to a steam boiler and a chamber for graphite surrounding said portion, said lubricator being formed with an internal valve seat adjacent the lower end of the central tubular portion and with a passage connecting said chamber and the interior of the tubular portion just above the valve seat, a manually adjustable valve to control the effective area of said passage, a dumb-bell piston valve mounted within said tubular portion and adapted to engage said valve seat, said valve being subject to the steam pressure of said boiler at its upper end, said valve body being adapted to connect to the discharge pipe of a main lubricator and receive lubricant and boiler pressure therefrom, said valve having a central longitudinal passage to permit the passage of said lubricant, and an abutment ring adjustably mounted in the upper end of the tubular portion to limit the movements of said valve.

ELIJAH McCOY.
